UNITED STATES PATENT OFFICE.

N. W. GORDON, OF WAUPUN, WISCONSIN.

IMPROVEMENT IN COUPLINGS FOR VEHICLES.

Specification forming part of Letters Patent No. 56,207, dated July 10, 1866.

To all whom it may concern:

Be it known that I, N. W. GORDON, of the town of Waupun, county of Fond du Lac, in the State of Wisconsin, have invented a new and Improved Mode of Coupling Wagons; and I do hereby declare that the following is a full and exact description thereof, reference being had to the accompanying drawings, and to the letters of reference marked thereon, like letters representing like parts in the several figures.

The nature of my invention consists in dispensing with a king-bolt and substituting instead thereof two plates, each having dovetailed projections, and one fitting into the other.

To enable those skilled in the art to make and use my invention, I will proceed to describe its construction and operation.

In the drawings, Figure 1 represents a rear view of my invention without the tongue; Fig. 2, a top view of part of the axle; Fig. 3, an under-side view of the bolster; Fig. 4, the rear part of the tongue; Fig. 5, a section through the two dovetailed plates.

A represents an ordinary axle; B, the bolster. C is a plate attached to the underneath side of bolster, having a dovetailed projection, c. D is a plate, also properly secured, like C, to the top of axle, having a projection, d, into which c fits. E is the usual fifth-wheel.

It is well known that king-bolts are more or less liable to break, or other disarrangement leads to the letting down of the front part of the body of the wagon or other vehicle, leading to bad or serious consequences, while the front wheels with tongue, &c., go onward. To remedy this is the object of my invention.

The raised part d of plate D has a dovetailed cavity, d'. It is also open at the rear, at e. The projection c of plate C is also of dovetailed form, and it is of ring shape, not concentric, having a cavity, f, and an opening, g. The part c, fitting into d or its cavity d', takes the place of the king-bolt.

F is a part of the tongue, having a metal hoop, h, at its rear end. This is intended to embrace d, and to rest between the axle-tree and the bolster, the strain coming upon d.

Fig. 6 shows how c and d are fit into each other—that is, at the commencement. At this time the bolster is nearly at right angles to the axle. It is then turned in the direction of the arrow i, after c is inserted into d, and given about one and one-quarter revolution. This completely secures c in d. Before doing this, however, the hoop of the tongue is put over d, as shown. In the position shown it permits the insertion. When, however, the tongue is turned to the front and the bolster has its proper position the hoop h assists in preventing any separation of the parts.

Having thus described my invention, what I claim as new, and desire to secure by Letters Patent of the United States, is—

1. The combination of the plate C with the bolster B.
2. The combination of the plate D with the axle A.
3. The combination of plates C and D, constructed and operating substantially as described, and for the purpose set forth.

N. W. GORDON.
